US0D1113573S

(12) **United States Design Patent** (10) **Patent No.:** **US D1,113,573 S**
(45) **Date of Patent:** **** Feb. 17, 2026**

(54) **BUCKLE**

(71) Applicant: **Shenzhen Litongda Garment Accessories Co., Ltd.**, Shenzhen (CN)

(72) Inventors: **Yaping Li**, Shenzhen (CN); **Yuying Zheng**, Shenzhen (CN)

(73) Assignee: **Shenzhen Litongda Garment Accessories Co., Ltd.**, Shenzhen (CN)

(**) Term: **15 Years**

(21) Appl. No.: **29/955,815**

(22) Filed: **Aug. 5, 2024**

(51) LOC (15) Cl. **02-07**

(52) U.S. Cl.

USPC **D11/209**; D2/853

(58) **Field of Classification Search**

USPC D11/200, 201, 208, 209; D2/706, 853
CPC A41F 1/006; A44B 13/0052; A44B 13/00;
A44B 13/0011

(57) **CLAIM**

The ornamental design for a buckle as shown and described.

DESCRIPTION

FIG. 1 is a perspective view of a buckle, showing our new design;

FIG. 2 is a front view thereof;

FIG. 3 is a rear view thereof;

FIG. 4 is a right view thereof, the left view being a mirror image;

FIG. 5 is a top view thereof;

FIG. 6 is a bottom view thereof; and,

FIG. 7 is a right view thereof showing our design in a combined state.

The spaced apart elongated rectangles, which protrude from the surface, represent stitching that is included in the claim.

1 Claim, 6 Drawing Sheets
